M. KLOPP.
WAGON BED.
APPLICATION FILED JAN. 31, 1914.

1,149,069.

Patented Aug. 3, 1915.

UNITED STATES PATENT OFFICE.

MICHAEL KLOPP, OF CINCINNATI, OHIO.

WAGON-BED.

1,149,069.

Specification of Letters Patent. Patented Aug. 3, 1915.

Application filed January 31, 1914. Serial No. 815,676.

To all whom it may concern:

Be it known that I, MICHAEL KLOPP, a citizen of the United States, residing at Cincinnati, in the county of Hamilton and State of Ohio, have invented certain new and useful Improvements in Wagon-Beds, of which the following is a specification.

My invention relates to wagon beds, and more particularly to that class of wagon beds used on oil tank, beer, ice wagons and the like.

The object of my invention is to provide a neat, efficient inexpensive and most durable frame for wagon beds.

15 My invention consists of constructing a wagon bed in a new and novel manner to produce a strong, neat appearing and efficient wagon bed, and one which is inexpensive to manufacture and which eliminates 20 all unnecessary wooden structure.

In wagon beds of the ordinary wooden construction the wood therein quickly decays and rots, particularly in wagons where the product carried, together with the 25 exposure to the weather, affects the wood.

In the drawings: Figure 1 is a perspective view of the inner channeled metal frame as it appears when used separately for use on tank wagons, and showing the usual fixtures 30 mounted thereon for the attachment of the springs, brake levers, etc. Fig. 2 is an assembled view showing my complete device, the floor being broken away for the sake of clearness. Fig. 3 is a plan view of the outer frame employed in my invention. Fig. 4 is a sectional perspective view of one of the 35 sills of the wagon bed. Fig. 5 is a longitudinal section taken on the line 5—5 of Fig. 2. Fig. 6 is a perspective view of a fragment 40 of the sill of the inner frame showing the welded joint of the cross channeled support. Fig. 7 is a perspective view of one of the fixtures placed on the frame.

Referring more particularly to the drawings, 1 illustrates the inner channeled metal frame, which is adapted to be placed inside of another channeled metal frame 2. The channeled metal frame 1 comprises channeled metal sills 3 and channeled metal cross 45 supports 4 welded thereto, thereby constituting a channeled metal wagon bed frame made practically of one piece of channeled metal material. The sills 3 have their channels facing outwardly, in order to provide 50 for a wooden filler and reinforcing member

5 when the two frames are used together, to form a most durable wagon bed frame. These fillers extend the entire length of the wagon bed frame. The outer channeled metal frame 2 comprises the sills 6 and 7, 55 which are preferably bent at right angles at the rear to form the finished back 8 of the wagon bed. These rear angular extensions 6' and 7' are bolted to the inner frame 1. The channeled sills 6 and 7 on the outer frame face inwardly and the wooden filler or reinforcing member 5 is then placed half in said channel on the outer sills 6 and 7, and half in the channels of the inner sills 3 60 of the inner frame, allowing the edges of the channeled sills to engage each other, thereby producing a most efficient sill for the wagon bed. By placing the wooden sills inside of the channeled sills they are securely bound together and form a most rigid sill which is 65 best adaptable for wagons used for heavy 70 hauling.

The wooden filler 5 by being mounted in the manner described is thoroughly protected from exposure to the weather by the 75 channeled sill on the inner and outer frames, and forms an efficient reinforcing and binding member for the metal sills.

The outer frame comprising the sills 6 and 7 is bent at the fore end to form a support 80 for the steps of the wagon as shown at 9 and 10, and is connected at the fore end by the cross channel iron 15, and at the rear with a corresponding cross channel iron 16. The frames are securely bolted together by 85 the bolts 10' and when properly constructed and assembled produce a wagon bed which is 90 most efficient, durable, economical to manufacture and neat in appearance.

A great advantage in constructing the 95 sills of channel metal with the wooden filler and reinforcing member, as described, is, that it is not necessary to further reinforce the sill with long iron plates when constructing platform wagons, that is, without sides, 100 or where the lower frame or bed is used only. This is absolutely necessary with wooden sills to prevent the same from sagging.

Metal wagon beds have not been placed on the market extensively, because of the 105 fact that the expense of manufacturing was greater than that of wooden ones, and they were invariably too heavy for practical use.

My improved body is light in weight, sim- 110

ple in construction and neater in appearance than those now made, due to the novel features of construction which it embodies.

The cross supports on the wagon bed are 5 preferably welded in position to the sides of the metal sills and are thereby secured against any joints breaking on account of weak bolts, which is so often the case with the wooden beds where the bolts are used. 10 Thus this feature overcomes any liability of the wagon bed spreading due to a bolt breaking.

The channelled metal cross supports preferably have the channels facing upwardly 15 and are filled with wooden fillers 20 flush with the top of the channels when a flat bottom is used. However, when the frame is to carry a cylindrical or square tank, the wooden fillers 20 are larger and extend up 20 and beyond the flanges of the channelled cross supports, thereby forming tank support blocks which are provided with cut surfaces 21 to receive and properly support the oil tank, as shown in Fig. 1. In this particular oil tank type where the sills are not required to support so much weight, the outer frame and wooden filler may be eliminated as shown in Fig. 1. The wooden supports are placed in the channelled metal cross 25 supports to form a bed or support for the tank. The bed when used in this manner is provided with extensions at the front to be used for the toe board 11 as shown in Fig. 1.

When the inner frame is used as illustrated in Fig. 1 the fixtures consisting of the shackles 12, used for the attachment of the springs, and the posts for the brake levers, are riveted to the sills 3, the bolts having spacing sleeves 14 between the flanges of the 30 sills to properly brace same. Channelled metal cross supports 17 are provided near the front of the frame shown in Fig. 1, to which the fifth wheel of the wagon is fastened, which in turn is mounted on the 35 wagon gear. These supports are bolted to the inner side of the frame, having the channels facing downwardly, and are bent at 18 to carry the wagon frame at the proper 40 height from the wagon gear.

50 Certain modifications of my invention might be made without departing from its

spirit and scope, and I do not wish to be confined to the exact details shown.

What I claim as new and desire to secure by Letters Patent is:

55 1. In a wagon bed and in combination, a channelled metal outer frame having the channels thereof facing inwardly, the channelled metal inner frame fastened thereto and having the channels thereof facing outwardly, channelled metal cross supports on said inner frame, and wood fillers in between said inner and outer frames filling the channel of each substantially as set forth.

60 2. In a wagon bed and in combination, an inner channelled metal frame comprising channelled metal sills connected by transverse channelled metal supports, an outer channelled metal frame comprising channelled metal sills, said outer frame surrounding two sides and one end of said inner channelled frame, and a wooden filler being surrounded by the sills of said inner and outer channelled metal frames.

65 3. In a wagon bed and in combination, an inner channelled metal frame having the channels thereof facing outwardly, an outer channelled metal frame having the channels thereof facing inwardly, a wood filler adapted to fit into and fill the channels of each of said frames at the sides thereof, said outer channelled metal frame being fastened securely to said inner frame clamping said wood filler therebetween, and channelled metal cross supports upon said inner frame, substantially as set forth.

70 4. In a wagon bed and in combination, an inner channelled metal frame having channelled metal cross supports thereon, an outer channelled metal frame fastened to said inner frame on three sides thereof, and curved portions at the front of said outer frame.

75 5. A wagon bed comprising channelled metal sills having the channels thereof facing outwardly, channelled metal cross supports having the channels thereof facing upwardly, and tank supporting blocks in the channels of said cross supports.

80 MICHAEL KLOPP.
